UNITED STATES PATENT OFFICE.

MAGNUS A. THOMSEN, OF OAKLAND, CALIFORNIA.

SHOCK-ABSORBER.

1,129,819.

Specification of Letters Patent. Patented Feb. 23, 1915.

Application filed January 5, 1914. Serial No. 810,801.

To all whom it may concern:

Be it known that I, MAGNUS A. THOMSEN, a citizen of the United States, residing at Oakland, in the county of Alameda and State of California, have invented certain new and useful Improvements in Shock-Ab-sorbers, of which the following is a specification.

This invention relates to improvements in vehicle springs and more particularly to the type of auxiliary springs commonly known as shock absorbers, and has as its object the construction of a device of this character, which is readily attached between the vehicle axle and frame, and which will gradually stop the relative movement between the same in either direction in which such movement may take place.

Another object of my invention is to use a leaf spring instead of the helical springs commonly used thereby enabling greater strength and rigidness to be secured.

With these and other objects in view my invention consists in the new and novel construction and combination of parts as herein described and illustrated in the drawings forming a part thereof.

Referring to the drawings: Figure 1 is a view in side elevation of a portion of a vehicle frame and axle showing my device attached therebetween. Fig. 2 is a view in elevation of the device in its normal position. Fig. 3 is a view in side elevation of the same.

Denoting corresponding parts by the same numerals of reference, 1 is the rear portion of the frame of the vehicle body and has suspended thereto the semi-elliptical spring 2, the latter being fastened to the axle 3 in any preferred manner.

My device consists of a rigid member 4 attached preferably to the frame 1 and a spring member 5 attached to the axle 3. The former consists of two depending wedge shaped portions 6 and 7 converging toward each other, the apexes being connected by the straight portion 8. 6, 7 and 8 are provided with broad faces 9 adapted to receive a pair of rollers carried by the spring member 5. Each of the wedge shaped portions has a cutout center 10 to lighten the device and to provide flanges 11 and 11', connecting the wide end of the wedge shaped portions. Through flange 11 bolts 12 pass, fastening the member to the frame 1, and to flange 11' is attached a cy-

lindrical rubber bumper 13, which coacts with a similar alining bumper 14 carried by the spring clamp 15.

The spring portion 5 consists of a plurality of leaves 16 each consisting of two parallel strips connected by a strip at the center in substantially the shape of a letter H. These leaves are then bent into U shape with the connecting strip as the axis forming two pairs of parallel spring arms and are then clamped to the axle by member 15. In this position the depending member extends into the openings between the spring arms of both pairs and the inner leaves of each pair are provided with alining eyes 17. A pin 18 extends through these eyes whereon is mounted a roller 19 between the arms and in such a manner as to contact with the faces 9. Now it will be apparent that as long as the frame and axle remain stationary with respect to each other the spring 5 will exert no action as the rollers 19 are resting against the parallel surfaces of portion 8. When however, the wheel is raised as in going over an obstruction these rollers are forced up the inclined faces of wedge 6 and the tension of the spring thus brought into action will tend to resist such movement and so gradually bring the parts to rest. In like manner when the wheel drops into a depression the rollers are forced along the inclined faces of wedge 7 with the same effect. To prevent damage in case of a very great shock bumpers 13 and 14 are provided to keep the metal parts out of contact and provide a cushion therebetween.

While I have illustrated and described the preferred embodiment of my invention it will be understood that changes may be made in minor details and form of parts without departing from the spirit thereof.

What I claim as new and wish to cover by Letters Patent is:—

1. A shock absorber for vehicles comprising a rigid member attached to the vehicle frame, a U-shaped leaf spring attached to the axle thereof, the said rigid member having oppositely disposed converging surfaces connected by contracted portion, the said spring carrying rollers on each arm thereof, the said rollers contacting with opposite surfaces of said rigid member and resting normally in the contracted portion thereof, so that movement between the parts in either direction will cause stress in the said spring.

2. A shock absorber for vehicles comprising a rigid member having double diverging roller surfaces with the contracted portions adjacent each other and connected by parallel roller surfaces, the said member being mounted upon the vehicle frame, a leaf spring of substantially U-shape mounted upon the said vehicle axle and having a transverse slot in the two arms in which the said rigid member moves, eyes on the end of the two pair of arms thus formed, a pin held in said eyes and having a roller pivotally mounted thereon within the said trans-

verse slot, the said rollers being adapted to contact with the opposite faces of said rigid member, so that movement between said frame and said axle in either direction is resisted by the forcing apart of said spring arm as the rollers move along the said diverging surfaces. 15

In testimony whereof I affix my signature in presence of two witnesses. 20

MAGNUS A. THOMSEN.
